CLAIM

The ornamental design for a confectionery package with small flap, as shown and described.

DESCRIPTION

FIGS. 1 and 2 are front and rear perspective views, respectively, of a first embodiment of the confectionery package with small flap of the present invention.

FIGS. 3, 4, 5 and 6 are plan views of the front, one end, rear, and other end, respectively, of the confectionery package with small flap of FIG. 1.

FIGS. 7 and 8 are top and bottom plan views, respectively, of the confectionery package with small flap of FIG. 1.

FIG. 9 is a front perspective view of the confectionery package with small flap of FIG. 1 in the opened condition with a small flap closed.

FIG. 10 is a front perspective showing of the confectionery package with small flap of FIG. 9 with the small flap shown open.

FIG. 11 is a rear perspective view of the confectionery package with small flap of FIG. 10.

FIGS. 12, 13, 14 and 15 are plans views of the front, one end, rear, and other end, respectively, of the confectionery package with small flap of FIG. 10; and

FIGS. 16 and 17 are top and bottom plan views, respectively, of the confectionery package with small flap of FIG. 10.

The broken phantom lines are for environmental purposes only and form no part of the claimed design.
